US00D543657S

(12) **United States Design Patent** (10) **Patent No.:** **US D543,657 S**
(45) **Date of Patent:** **** May 29, 2007**

(54) **LAMPHOLDER**

(75) Inventor: **Gregg Lehman**, Peachtree City, GA (US)

(73) Assignee: **Cooper Technologies Company**, Houston, TX (US)

(**) Term: **14 Years**

(21) Appl. No.: **29/251,913**

(22) Filed: **Jan. 13, 2006**

Related U.S. Application Data

(63) Continuation of application No. 29/233,364, filed on Jun. 30, 2005.

(51) **LOC (8) Cl. 26-99**

(52) **U.S. Cl. D26/138**

(58) **Field of Classification Search** D26/138, D26/72, 75, 76, 81, 113, 141, 155, 118, 119, D26/128; 362/269, 234, 247, 282, 147, 217, 362/257, 260, 382, 404, 432; D6/308; 40/715

See application file for complete search history.

(57) **CLAIM**

The ornamental design for a lampholder, as shown and described.

DESCRIPTION

This application is related to co-pending applications: Ser. No. 11/322,837, filed Dec. 30, 2005 and titled “Halo Flex Track”; Ser. No. 11/324,099, filed Dec. 30, 2005 and titled “Halo Power Supplies”; Ser. No. 11/323/231, filed Dec. 30, 2005 and titled “Halo Clam Shell Connections”; and Ser. No. 11/323/755, filed Dec. 30, 2005 and titled “Halo Hubs and Connections”.

FIG. 1 is a top, front perspective view of a first embodiment of a lampholder showing my new design;

FIG. 2 is a front view thereof;

FIG. 3 is a left end view thereof;

FIG. 4 is a top view thereof; and,

FIG. 5 is a top, front perspective view of a second embodiment of a lampholder showing my new design.

The broken lines form no part of the claimed design.

1 Claim, 3 Drawing Sheets
